UNITED STATES PATENT OFFICE.

CARL NOURNEY, OF BERLIN-WILMERSDORF, GERMANY.

TRANSLUCENT LUMINOUS ADVERTISING MIRROR.

Application filed March 1, 1915. Serial No. 11,433.

To all whom it may concern:

Be it known that I, CARL NOURNEY, a subject of the German Emperor, and resident at 45 Landhausstrasse, Berlin-Wilmersdorf, 5 Germany, have invented certain new and useful Improvements in a Translucent Luminous Advertising Mirror, of which the following is a specification.

The present invention relates to a translucent luminous advertising mirror, the advertisement band of which is intermittently controlled and intermittently illuminated by electromagnetic means.

For allowing that the duration of the interval may be accurately regulated at will, the present invention provides besides the electromagnet controlling the advertisement band, a second electromagnet connected therewith, the displaceable iron core of which second electromagnet has at its lower end a piston, moving in a pneumatic cylinder serving as a brake, and having at its upper end a contact plate, so that when the current is switched on, the piston will, correspondingly to the resistance of the air be slowly forced upwards by the electric magnet and the contact plate lifted, and retained in such position until the two electromagnets are again switched off, after such switching off the piston slowly sinks until the contact plate has again reached the contacts and thereby again switches the electromagnets on. The duration of the break may be regulated by regulating the pneumatic resistance in the cylinder, for example by turning a regulating screw provided in the same.

In the accompanying drawings a constructional form of the present invention has been exemplified.

Fig. 1 is a front elevation while the current is switched off.

Fig. 2 is a side elevation and sectional view through the casing.

Fig. 3 is a plan view of the switch for the coupling, intermittently operated by the advertisement band, during the contact;

Fig. 4 is the same, while switched off;

Fig. 5 is a plan view of the switch device;

Fig. 6 is a front elevation of the same;

Fig. 7 is a side elevation of the same;

Fig. 8 is a side elevation of the coupling switch intermittently operated by the advertisement band;

Fig. 9 is a front elevation of the same;

Fig. 10 is a plan view of the same;

Fig. 11 is a rear view of the same;

Fig. 12 is a diagram of the connections.

The electromotor 2 fitted to the casing 1 drives the shaft 3, the worm 4 and the worm wheel 5. The horizontal shaft of the worm wheel carries a bevel gear 6, with which mesh the bevel gears 7 and 8. The bevel gear 7 is fitted loose on its shaft 9 to the end of which is displaceably fitted the coupling sleeve 10. When this sleeve is forced against the bevel gear 7 it engages with the coupling member 11 of the bevel gear 7, so that the shaft 9 is driven. To the free end of the latter is fitted a sprocket 12 which by means of a chain 13 drives the sprocket 14 and the roller 15. Thereby the advertisement band 16 is wound on the roller 15. Opposite to sleeve 10 a sleeve 18 is displaceably fitted on shaft 17. When this sleeve 18 is approached to the bevel gear 8, running loose on its shaft, the shaft 17 is rotated and with it the sprocket 19, which by means of chain 20 drives the sprocket 21 and the upper roller 22, which winds up the advertisement band at the top. The sleeves 10 and 18 have each a collar 23 and both collars are engaged by a fork 24 disposed behind them. The fork 24 is pivoted on a pin 25 and is made in one piece with the lever 26. To the bifurcated free end of lever 26 is hinged a rod 27, the other end of which is linked to a double-armed lever 28. The lever arm above the pin 29 is hinged to the iron core 30 by means of a screw 31. Accordingly as the current is switched on either the coil 32 or 33 is excited; thereby the clutch 10 or 18, respectively, is so engaged that either the lower roller 15, or the upper roller 22, respectively, is rotated for winding the band. For the intermediate position of the lever 28 to be accurately maintained while the coils 32, 33 are switched off, a horizontal bar 34 is provided over the said coils, in which bar pins 35, 36 are fitted. Against pin 35 bears a rubber washer 37, and against pin 36 a rubber washer 38. Springs 39 elastically press the rubber washers against said pins. The end of lever 28, extended above fits exactly into the gap between the washers, so that the lever must always maintain this intermediate position when the coils are switched off. When coil 32 is excited, the lever 28 will force the washer 37 aside. When coil 33 is excited, the lever 28 will force washer 38 aside. To the rear of lever 28 is fitted a part 40 forming an extension

thereof, which together with the lever extension in front of the rod 34 forms a fork, engaging said rod. This part 40 is provided at the rear with a horizontal pin 41 made of fibre. Above this pin a contact 42 is fitted to the casing 1, against which contact bear two contact springs 43, pivoted on pins 44 and drawn by a tensile spring 45 against the contact 42. The two contact springs close the lamp circuit as long as they contact jointly with the contact member 42. For switching off the lamp it is sufficient to remove one of the springs from the contact member 42. This removal is effected each time the clutch is engaged, as then the lever 28 forces off by part 40 the one or the other of the said springs 43.

Beside the coupling coils 32, 33 a coil 46 is vertically fitted to the casing (Figs. 1, 2, 20 and 5-7) and beneath this coil 46 a cylinder 47 is fitted. A rod 48 is disposed to rise and fall in both, and within the coil said rod carries an iron core, in the cylinder a piston. When the coil 46 is excited, 25 the rod will rise, because the core will be drawn into the coil. When the coil is switched off, the rod will descend, but very slowly, as the piston will have to force the air beneath it out from the cylinder through a small vent, regulable by means of screw 49. To the upper end of rod 48 is fitted 30 an insulated contact plate 50. As soon as the latter sinks with the rod, it contacts with the contacts 52 on the fiber plate 51, and thereby closes the circuit.

Beneath the winding roller 22 a switch is provided at the left side (Figs. 1-4). This switch consists of the double-armed lever 53 pivoted on a screw 54. The upper end is 40 drawn backwards by spring 55, whereby the lower end, carrying a fiber roller 56 is forced forward. The double-armed lever has about its middle the contact arm 57, which, when the lever 53 is moved, rocks towards or away from the contact member 58. As the roller 56 lies in the path of the bars 45 79 of the advertisement band, the latter will intermittently press the roller backwards, and thereby switch off the current.

On the right side of the casing is disposed beneath the winding roller 22 a switch for the excitors of the electric magnets 32, 33 for operating the clutch 10, 18. This switch is intermittently reversed by the bars 55 of the advertisement band, namely by the first and by the last for reversing the winding on rollers 15, 22. This switch (Figs. 8-11) consists of a casing, 59, which is pivoted on a pin 60. On the inner side of 60 the casing is fitted an insulated contact arm 61, which according to the manner in which it is set, or the casing is set, will form a bridge over the contact arms 62/64 and 64/63. The oscillation of the casing is limited by the yoke 65 through the middle of

which passes the shaft 69 rotatably journaled in plate 66. On this shaft is fitted a contact lever 67 insulatedly secured behind the plate and rocking between the contacts 68, and bearing against the one or the other of the contacts, according to the manner in which the casing is set. Within the casing 59 a triangular brake member 70 is fitted to shaft 69, which brake member will switch off the current for one moment 75 in such a manner, that the picture will not go beyond the brake member and will not be torn. The brake member projects with its point into the casing. In front of this point a slide 71 is disposed in the casing, 80 which is wedge shaped towards the said point and is held pressed against the brake member by means of spring 72. To the front of the casing is riveted a pin 73, which, when the casing 59 rocks, will glide 85 with its inner, flattened side over the rectangular face of the brake member. In the middle of the rectangular face of the brake member is provided a recess 74. In each of the side walls of the casing is provided 90 a slot 75 through which passes the shaft 69. When the lug 76 (Fig. 8) fitted to the bar 79 of the advertisement band engages the pin 73, the casing 59 will rock over and in consequence of such rocking of the casing and the brake member the switching of 95 levers 61/67 will be effected extremely quickly against the action of the slide 71 which is thereby temporarily pushed back. The contact levers, besides, will not stop 100 half way, but will always be forced into the full contact position and there retained. A last switching means is the coil 77, the 105 electromagnet of which attracts the lever 78 rocking on the pivot 80. Thereby the contact 78/81 is closed, and the coil 46 is switched on. After the current has been switched off, the lever 78 will, by its own gravity fall back into the position shown 110 in Fig. 2.

In the diagram Fig. 12 also the connection of the resistances has been included, which must be employed when, instead of 110 volts, a higher pressure, say 220 volts is employed. The resistances are preferably disposed in the top of casing 1 in the space 82' enclosed by a perforated sheeting. For switching these resistances special switches are used namely switch 82 for the reversing switch, 83 for the air cushion and the magnet coil, 84 for the lamps and 85 for the motor. By means of the plug contact 86 the device may be connected with an existing circuit.

The modus operandi of the invention is as 125 follows:—

Upon closing the switch 86, a circuit will be completed to the motor 2, continuously rotating the same. The switch 57 being 130 normally closed, will, at the same time, ef-

- fect a circuit through the solenoid 77, the switch 67, and the solenoid 32, to the switch 82; the solenoid 77 magnetically causing contact between the points 78 and 81 will effect 5 a circuit through the solenoid 46, holding the switch 50 open, while the solenoid 32 opens the light circuit through the contact 43 and causes the clutch 10 to engage with the motor driven gear 7. This clutch 10 10 being keyed to the shaft 9, will rotate the same, and thereby rotates the rollers 15 and 22, causing the curtain to move downward until a display registers with the window. At this time, a projection on the curtain 15 striking the roller 56 will break the circuit through the switch 57, allowing the lever 28 to swing to a central position thereby disengaging the clutch 10 and simultaneously completing the circuit to the lights through 20 the switch arms 43. At the same time, the solenoid 77 being deenergized, the circuit through the contacts 78 and 81 will be broken, thereby deenergizing the solenoid 46 and allowing the piston to settle slowly in 25 the dash pot 47 until the switch 50 closes and completes a circuit through the switch 6 to the solenoid 32, causing the same to switch off the lights and again start the curtain in motion and allowing the switch 57 30 to again close. After this, the operation will be repeated until the curtain becomes completely unrolled from the roller 22, at which time, another projection on the curtain will cause the switch arms 67 and 61 to break the circuit to the solenoid 32 and to complete the circuit to the solenoid 33, causing the clutch member to engage the gear 8 and reverse the direction of rotation of the rollers. The curtain becoming completely 35 unrolled from the roller 15, another projection will cause the switch arms 67 and 61 to resume their first position, thus repeating the operation.
- I claim:
- 45 1. A device of the character described comprising a casing having a window therein, transversely disposed rollers mounted in the upper and lower portions of said casing, a translucent web windable upon said rollers, illuminating means within the casing rearwardly of said web, a motor driven shaft within the casing, means for selectively and 50 mechanically connecting said motor driven shaft to the rollers whereby to effect selective rotation thereof, opposed magnetic means in the casing having a core common to each connected to said last mentioned means, opposed electrical circuit closing means in proximity to the core and adapted to be individually closed for controlling said illuminating means, other electromagnetic means in the casing, a core movable longitudinally through the same, an electric contact plate carried on said last core, electric contacts on the last mentioned electromagnetic means, means connected to said last mentioned electromagnetic means for cushioning return movement of the core to normal position with deenergization of such electromagnetic means, electric contacts on the last mentioned electromagnetic means engageable with said contact plate for effecting intermittent energization of said first electromagnetic means, other electromagnetic means within said casing and electrically connected to the first mentioned electromagnetic means, and mechanically operable circuit closing means adapted to be actuated by movement of the translucent web thereby connected to said other electromagnetic means for effecting selective energization of the first mentioned and opposed electromagnetic means.
- 55 2. A device of the character described comprising a casing having a window therein, transversely disposed rollers mounted in the upper and lower portions of said casing, a translucent web windable upon said rollers, illuminating means within the casing rearwardly of said web, a motor driven shaft within the casing, gears upon said shaft individually connected to the rollers for rotating the same, clutch means movable on the shaft for selectively connecting said gears thereto, opposed electro-magnetic means in the casing having a core common to each, means connecting said core to the clutch means, opposed electrical circuit closing means in proximity to said core adapted 60 65 70 75 80 85 90 95 100 105 110 115

In testimony whereof I have hereunto signed my name this 13th day of February 1915.

CARL NOURNEY.
